DES. 2268

Joseph Scheler of Hudson City, N. J.

assente

The American Lead Pencil Company, of New York, N. Y.

Letters Patent No. 2268-Dated July 27-1866.

Design for a Trade Mark.

The schedule referred to in these Letters Patent and making part of the same.

It all where it may concern:

Be it known that Joseph Scheler, of Henderson City, in the County of Hudson and State of New Jersey, has invented and designed for a Trade Mark, to be used on Lead Pencils, and on the packages or labels for containing the same; and I do hereby declare that the following is a full, clear and exact description of the same, reference being had to the accompanying drawings forming a part of this specification, in which:

Figure 1 represents the design on an enlarged scale and

Figure 2 represents a black lead pencil with the design printed, embossed, or stamped on the one end thereof.

The design which may be printed directly upon the pencils or upon the packages or wrappers containing them, or on labels attached to said wrappers or to boxes intended to contain the pencils, represents the wings of a Caduceus or Mercury's Wand, consisting of the stem of the wand spirally entwined by the wings and each one encircling the stem in opposite directions and terminated by the proper cap.

DES. 2268

2

Accompanying this figure and forming a part of the design is the word 'Empire' which is intended to be impressed, printed or otherwise placed upon the pencil, package or label, in about the position shown in fig. 2 in relation with the previously described figure.

What I claim as my design and desire to secure by Letters Patent is

The design and configuration of the herein described Trade Mark consisting of a 'Cadicui' or 'Marsupij' Mandi, and the word 'Empire' as shown in the annexed drawings.
